2 Sheets-Sheet 2

UNITED STATES PATENT OFFICE

LELAND K. BUTLER, OF MANCHESTER, NEW HAMPSHIRE, ASSIGNOR, BY MESNE ASSIGNMENTS, TO EXCEL TAPING MACHINE CO., OF LYNN, MASSACHUSETTS, A CORPORATION OF MASSACHUSETTS

TAPE-APPLYING MACHINE

Application filed April 5, 1928. Serial No. 267,714.

This invention relates to a machine for applying reinforcing tape to sheets of material, such as the uppers of shoes, and more particularly to marginal portions thereof, and in some aspects comprises an improvement upon the apparatus disclosed in the co-pending application of Jerome P. Byron No. 216,702, filed August 31, 1927.

The above identified pending application discloses in general mechanism particularly adapted to apply tape coated with permanently plastic adhesive and to permit such operation continuously to be effected by the movement of the tape and the sheet between a pair of rolls which are yieldably urged toward each other. The present invention affords more simple and effective guide means for the sheet and for the tape and affords an arrangement of parts that permits the more facile and convenient manipulation of the sheet to permit the ready application of the adhesive tape to marginal portions of the sheet whether straight or curved. A further aspect of the invention relates to the arrangement of a tape roll and an intermediate idler roll in order to permit a suitable pull to be cast upon the tape to overcome the adhesion between adjoining turns of the same in the tape roll. Another aspect of the invention relates to the arrangement of parts which permits the coated tape to be protected against accidental engagement with foreign objects and particularly against engagement with a part of the sheet aside from that to which it is to be properly applied. Furthermore, these means are arranged to permit the convenient changing or replacement of tape rolls and the ready feeding or training of a new tape roll about the various parts of the machine. Another feature of the invention prevents the adhesive tape from sticking to the tape-applying rolls if there is no sheet material interposed therebetween.

A machine which exemplifies the invention is illustrated in the accompanying drawings, in which:

Fig. 1 is a front elevational view of the improved tape-applying machine;

Fig. 2 is a side view of a portion of the same;

Fig. 3 is a top view of a part of the assembly shown in Fig. 2;

Figs. 4 and 5 are detail elevational views of the tape-applying rolls showing various selected positions of the same; and

Fig. 6 is a sectional view through one of the rolls, showing related parts.

A machine of the type exemplified in the accompanying drawings preferably comprises a frame, designated in general by the numeral 1, which may be mounted upon any suitable table or support. One end of frame 1 preferably supports a train of gears, designated in general by the numeral 2. This gear train is driven from any suitable source of power by a belt 3 passing over a pulley 4 which is provided with a weighted rim 5 that not only comprises a flywheel but also forms a hand wheel to permit manual movement of the parts in order to permit accurate adjustment of the machine for the insertion of new work or any other desired purpose. Mounted above frame 1 is a transverse shaft 7 which is rotated by the gear 8 which is loosely meshed with an adjoining gear 9 of the train 2. The shaft 7 is carried upon an upper roll support 12 which is pivotally connected to the frame 1 adjoining the gear train, as designated by numeral 13. The overhanging end of shaft 7 opposite the gear 8 carries a unit 10 for pressing the sheet material against the adhesive tape. The weight of the support 12 as well as any suitable spring, not shown, may serve to press the roll 10 downwardly toward a lower tape-applying roll 20 which is rotatably mounted upon the frame 1. Roll 20 is mounted upon a shaft 11 which extends through frame 1 and carries the gear 9 at its opposite end.

A depending box-like portion 15 of support 12 may interfit with the upstanding projection 16 upon frame 1 to serve as a guide for the support. It is evident that the loose meshing engagement of the gear 8 with the adjoining driving gear 10 co-operates with the pivotal mounting of support 12 to permit the rolls 10 and 20 to separate to allow the interposition of sheet material and tape therebetween.

A bracket 30 extends outwardly from frame 100

1 and supports a suitable axle 31 upon which a tape roll 32 may be located. Preferably this roll may be formed of tape that is coated with a permanently plastic adhesive which 5 may be pressed into engagement with a sheet at ordinary temperature. The roll 32 preferably is surrounded by a suitable guard 35 comprising opposite plates 33 and 34. One of these plates, i. e. plate 34, is fixed to bracket 30 and preferably carries a roller 36 about 10 which the tape run may be turned, this roll preferably being located in substantially the same horizontal plane as the axis of roll 20, Fig. 2, and the tape run extending therefrom 15 about the lower portion of the latter roll so that it is wrapped about a considerable peripheral portion of the same to ensure a firm frictional engagement between this roll and the tape. Plate 34 carries a curved flange 37 20 surrounding a peripheral portion of the tape roll, Figs. 1 and 3. The removable plate 33 preferably is provided with a set screw 68 engaging axle 31 to permit the ready removal of plate 33 and the replacement of the 25 tape roll when necessary.

Adjoining the juxtaposed portions of rolls 10 and 20 is a suitable guide member 41 which is adjustably mounted upon the frame 1. This member comprises a finger 42, the 30 curved end of which is adapted to lie adjoining the inner face of roll 10. Finger 42 is supported by an upstanding element 43, the lower portion of which is bent outwardly and provided with a slot 44 to receive the fastening 35 element 45, whereby the finger 42 may be adjusted inwardly in relation to the rolls. As shown in Fig. 2 the intermediate portion 43 of member 41 is angularly disposed in relation to the lower plate portion so that finger 42 is located somewhat in advance of the 40 point where the rolls 10 and 20 tend to contact or substantially contact.

Adjoining guide member 41 is a tape guide 50 which comprises a segmental portion 51 having a curved channel or slot therethrough. This guide also may be provided with an intermediate supporting portion and a lower plate portion 5 which is slotted, as designated 55 by numeral 56, to receive fastening means 55. Preferably the slotted portion 51 has a suitable width properly to receive and guide the particular type of tape which is to be used in the machine, it being obvious that a plurality of the guide members 50 may be supplied to accommodate tapes of various widths. The 60 tape guide is laterally adjustable due to the arrangement of slot 56 so that it properly may be positioned in relation to rolls 10 and 20.

65 A guard or scraper 60 is secured to the back of the support 13 and curves inwardly and downwardly toward the face of roll 10 so that its edge is disposed close to the back of that roll.

65 A suitable guard 65 is arranged about the

front of roll 20 to prevent accidental engagement of foreign objects with the adhesive face of the tape. This guard has its lower end pivotally connected to the frame 1, as 70 designated by numeral 66^a, and is provided with a curved flange extending upwardly from pin 66 and closely paralleling the front face of the roll 20. The guard also has a suitable side portion which carries a nub 67 that is adapted to engage the curved end 75 portion of a leaf spring 66 that is secured to the face of the frame 1, it being evident that a downward and outward pull upon the guard will cause the nub to engage the curved spring end with cam-like action to release the 80 guard and to permit the same to swing down away from roll 20, thus facilitating the feeding of a new run of tape about the lower roll and into the slotted portion 51 of the tape 85 guide.

The upper roll 10 is preferably provided with an intermediate portion 10^a having central bosses 70 and 71 fitted upon an extension of the shaft 7. This shaft has a shoulder 75 adjoining the end of support 12 and is provided with suitable key-like extensions or 90 projections 76 that seat in recesses on the boss 70. At either side of the intermediate roll section 10^a are other roll portions 10^b and 10^c, the former being engaged by the 95 detachable fastening element 72 which is threaded into the end of the shaft 7. The latter is preferably provided with a suitable annular recess which receives a washer 79, that is adapted to engage the end of support 100 12. Roll portions 10^b and 10^c preferably are mounted upon bosses 70 and 71 of section 10^a and are held between member 72 and washer 79 in such a manner that they are 105 retained in frictional engagement with the faces of the intermediate roll section 10^a, although they are adapted to be moved independently of the same in response to suitably applied exterior forces. A roll of this character is particularly suitable to permit 110 the application of tape along a curved path, the different portions of the roll being adapted to rotate at slightly different speeds in response to the speeds of different parts of the material which they engage.

Fig. 4 shows a roll 90 having a similar arrangement of roll sections to that described above and with the exception that the outer roll sections have narrow peripheral portions 80, but have their intermediate 120 portions of the same dimensions as the roll sections shown in Fig. 5 and described above. Thus the roll 90 may be used interchangeably with the roll 10 whenever a narrower tape applying roll is desired. While I have 125 shown the central roll section as the driving element and have shown a single driven roll element at either side thereof, it is evident that this arrangement may be varied, and that there may be a single driven 130

element or more than two driven elements, as circumstances may warrant, it being further evident that the driven element may be located centrally of the roll or toward one side thereof, as desired.

The diameters of the rolls 10 and 20 have substantially the same ratio as the pitch circles of gears 8 and 9, but I have found that in practice it is advantageous to vary these diameters somewhat to take care of the particular characteristics of the sheet material or the tape that is being used. Thus, for example, when the tape is quite yieldable and elastic, I have found it advantageous to so dimension rolls 10 and 20 that the lower roll has a somewhat greater peripheral speed than the upper roll. This arrangement compensates for the tendency of the tape to draw or reduce in length after passing between the rolls. Thus the sheet and adhesive tape remain united without any tendency to pucker or pull away from each other.

In the operation of a machine of this character, the plate 33 being removed, a suitable tape roll 32 is applied to the axle 31, the tape run being wrapped around the roller 36, if desired, and in any case being wrapped around the lower portion of roll 20 and fed through slot 51 in tape guide 50, the guard 65 being readily swung down to permit this action. Thereupon the plate 33 may be replaced to protect the adhesively coated face of the tape against engagement with foreign objects and the guard 65 may be swung up to its operative position. The sheet material to which the tape is to be applied is located with its edge in engagement with the end of finger 42, and the driving factor is started so that rolls 10 and 20 are rotated to draw the tape and sheet between the rolls and to press the tape firmly into engagement with the sheet. The arrangement of the finger 42 in advance of the juxtaposed portions of rolls 10 and 20 permits the convenient manipulation or lateral swinging of the sheet in relation to the tape-applying roll by the operator. Thus the tape may follow any suitable path, for example, being readily applicable to the curved edge portion of the front of a shoe upper. The scraper 60 prevents the adhesive face of the tape from clinging to the roll 10 if the rolls continue to rotate after the sheet material has passed between the same.

It is further evident that the provision of a roll having a plurality of sections, which may move at different speeds, permits the more convenient movement of the material along curved paths and permits the ready application of tape to the same.

I claim:

1. A machine for applying adhesively coated tape to sheet material comprising a pair of juxtaposed rolls, a tape roll arranged

to supply a tape run to be wrapped about one of said rolls and a guard adjoining said roll to protect the coated face of the tape, said guard being movably mounted to permit the ready wrapping of a new tape run about the roll.

2. A machine for applying adhesively coated tape to sheet material comprising a pair of juxtaposed rolls, a tape roll arranged to supply a tape run to be wrapped about one of said rolls and a guard adjoining said roll to protect the coated face of the tape, said guard being pivotally mounted, and a spring having a cam-like engagement with a portion of the guard to retain it in its normal position.

3. A machine for applying adhesively coated tape to sheet material comprising a pair of juxtaposed rolls, a tape roll arranged to supply a tape run to be wrapped about one of said rolls, and a housing about the tape roll and an adjoining part of the tape run, said housing comprising a removable plate to permit the replacement of the tape roll.

4. A machine for applying adhesively coated tape to sheet material comprising a pair of juxtaposed rolls, a tape roll arranged to supply a tape run to be wrapped about one of said rolls, a housing about the tape roll and an adjoining part of the tape run, and a fixed axle extending through the housing and supporting said tape roll, said housing including a removable plate, said plate being detachably secured to the axle to permit replacement of the tape roll.

5. A machine for applying adhesively coated tape to sheet material comprising a pair of juxtaposed rolls, a tape roll arranged to supply a tape run to be wrapped about one of said rolls and a scraper having an edge juxtaposed to the back face of one of the rolls to prevent the adhesive tape from continuing in engagement with said roll.

6. A machine for applying adhesively coated tape to sheet material comprising a pair of juxtaposed rolls, a tape roll arranged to supply a tape run to be wrapped about one of said rolls, one of said juxtaposed rolls having bosses of different dimensions at each side whereby it may be located in two selected positions determined by the position of these bosses in engagement with surrounding objects.

7. In a machine of the class described, a pair of juxtaposed rolls, a tape roll, an intermediate roll, said tape roll having its center disposed below the lower of the juxtaposed rolls, said intermediate roll being smaller in diameter than the lower of the juxtaposed rolls and having its center substantially in the same horizontal plane, whereby tape coming from the tape roll and led about the intermediate roll may be wrapped about the major portion of the periphery of the lower roll before passing between the juxtaposed rolls.

8. A machine for applying adhesively coated tape to sheet material comprising a pair of juxtaposed rolls adapted to receive the tape and sheet therebetween, one of said rolls comprising a plurality of sections providing a plurality of peripheral surfaces, one of said sections being positively driven, and another section being free from positive drive. 13. A machine of the class described comprising a pair of juxtaposed rolls, means for driving the rolls, a tape supplying means arranged to supply tape to a peripheral portion of one of said rolls which is disposed substantially 270° in a direction counter to that of the movement of that roll from the bite of the juxtaposed rolls, whereby the tape run may be in engagement with a considerable peripheral portion of said roll. 70
9. A machine for applying adhesively coated tape to sheet material comprising a pair of juxtaposed rolls adapted to receive the tape and sheet therebetween, one of said rolls comprising a plurality of sections providing a plurality of peripheral surfaces, one of said sections being positively driven, the other sections being driven by friction so that there may be relative movement between them and the positively driven section. 75
10. A machine for applying adhesively coated tape to sheet material comprising a pair of juxtaposed rolls adapted to receive the tape and sheet therebetween, one of said rolls comprising a plurality of sections providing a plurality of peripheral surfaces, one of said sections being positively driven, said section having outstanding bosses, the adjoining sections being mounted on the bosses and having surfaces held in frictional engagement with the sides of the positively driven section. 80
11. A machine of the class described, comprising a pair of juxtaposed rolls, means urging the rolls toward each other, means for driving the rolls, a support for a roll of adhesively coated tape arranged to supply a run of the tape to a peripheral portion of one of the rolls, an idler member adapted to engage the tape run, said idler member being disposed in the vicinity of a plane extending through the axis of the roll which receives the tape, said plane being substantially at right angles to a plane passing through the axes of the juxtaposed rolls, whereby the tape is supplied to a considerable peripheral portion of the roll before it passes between the juxtaposed rolls. 85
12. A machine of the class described comprising a pair of juxtaposed rolls, means for driving the rolls, a support for a roll of adhesively coated tape, said support being positioned so that the axis of the tape roll is disposed below a plane which is tangential to the nearer of the juxtaposed rolls and is normal to a plane extending through the axes of said juxtaposed rolls, an idler member arranged in a plane extending through the axis of one of said rolls and parallel to said first-named plane, said support for the tape roll and idler member being arranged so that the tape may be withdrawn substantially tangentially from the tape roll and may pass about a considerable peripheral portion of one of the juxtaposed rolls before passing to the bite of said rolls. 90
13. A machine of the class described comprising a pair of substantially parallel shafts, a roll mounted on each shaft, said rolls being juxtaposed, a tape guide adjoining one of the rolls and being arranged to supply tape to the bite of the rolls, common drive means for said shafts effecting the rotation of the shafts at speeds which have a predetermined ratio to each other, the ratio of the diameter of the roll remote from the guide to the diameter of the roll adjoining the guide being somewhat less than the ratio of the speeds of the corresponding shafts, whereby the roll remote from the guide has a peripheral speed slightly lower than that of the other roll. 95
- Signed by me at Boston, Massachusetts, this 23d day of March, 1928.
- LELAND K. BUTLER.
